UNITED STATES PATENT OFFICE.

WILLIAM LINCOLN DUNN, OF OXNARD, CALIFORNIA, ASSIGNOR TO THE DUNN MANUFACTURING COMPANY, OF OXNARD, CALIFORNIA, A CORPORATION OF CALIFORNIA.

HYDRAULIC ROTARY WELL-BORING TOOL.

1,193,247.

Specification of Letters Patent. Patented Aug. 1, 1916.

Application filed March 17, 1913. Serial No. 755,020.

To all whom it may concern:

Be it known that I, WILLIAM L. DUNN, a citizen of the United States, residing at Oxnard, in the county of Ventura and State of California, have invented a new and useful Hydraulic Rotary Well-Boring Tool, of which the following is a specification.

It frequently occurs in boring oil wells that the hole may be drilled to a depth of 10 2500 feet, more or less, without the necessity of inserting casing, but that at such depth it becomes necessary to insert casing in order to prevent the walls of the hole from caving in, and that after such casing has been inserted it is necessary to drill to a considerable depth, say, 500 feet, more or less, below the casing before the oil-bearing stratum is reached, and that the intervening depth must also finally be protected with casing. 15

It is desirable, of course, that the bore of the well be as large as possible from top to bottom, and an object of this invention is to provide a cheap, simple and effective hydraulic rotary boring tool by which the hole can be drilled from start to finish, with the necessity only of renewing from time to time cheap, conveniently replaced parts which are subject to wear. 20

Strength and rigidity of construction, ease 30 and convenience of taking out and replacing the cutting parts, and superior efficiency of operation are further objects of this invention.

Another object is to so mount the cutter blades as to maximize the effective cutting diameter of the blades so as to produce a bore of much greater diameter than the tool body, and notwithstanding which the blades may be folded within the compass of 35 well casing of but slightly larger diameter than the diameter of the tool body.

Other objects and advantages may appear as the invention is unfolded in the subjoined detail description.

The accompanying drawings illustrate the 45 invention.

Figure 1 is an elevation partly in section on irregular line indicated by x^1-x^6 Fig. 50 2 of a tool constructed in accordance with this invention. Fig. 2 is a view at right angles to Fig. 1, parts being broken away to expose interior construction. Fig. 3 is a view of the bottom end of the tool. Fig. 4 is a view of the bottom of the tool, the blades being cut away at line x^4-x^4 Fig. 2. Fig.

5 is a view of the tool partly in longitudinal section on irregular line indicated by x^1-x^5 Fig. 2 showing the tool when collapsed for the purpose of passing through a casing, a fragment of which is shown in section. Fig. 60 6 is a view of the tool in operative position to form an excavation, which is indicated, below the lower end of the well casing, a fragment of which is shown in section. Fig. 7 is a face view of one of the cutter blades 65 together with its forked rod which is partly broken away to contract the view. Fig. 8 is an elevation of Fig. 7 looking at the right-hand edge of the cutter blade. Fig. 9 is a plan section on line indicated by x^9-x^9 , 70 Fig. 6. Figs. 10 and 11 are fragmentary longitudinal sections on lines indicated by $x^{10}-x^{10}$ and $x^{11}-x^{11}$, respectively, Figs. 9 and 12. Fig. 12 is a view of the bottom end of the tool. 75

The body or case 1 of the tool is provided at its upper end with a tubular coupling pin 2, the central bore 3 of which is extended toward the lower end of the body, and communicates with two outwardly and downwardly sloping branches 4 opening at the bottom of said tool body 1 at opposite sides of the mid-plane thereof. Said branches 4 are of less diameter than the bore 3, and may be variously constructed and they serve as nozzles to direct streams of water as required underneath the body of the tool and outwardly along-side the cutter blades to loosen and wash out the shale, clay, and other materials which may be cut by the tool in its operation, and which material, as is customary in the operation of hydraulic rotary tools, is carried out up through the hole and around the rotary pipe and its box 5 to the surface of the ground. 90 95

On opposite sides of a determined mid-plane indicated by the line $a-a$ in Figs. 3 and 4, longitudinal slots 6 are provided, the sides of which are parallel, and the adjacent sides of which are formed substantially in 100 said mid-plane. These slots terminate respectively at their upper ends in sockets 7 which are formed between outer edge wall seat-forming portions 8 of the tool body and inner edge walls 9 that are aslant relative 105 to the axis of the tool, said inner edge walls slanting downwardly and inwardly and terminating at their lower ends to form guiding and stopping shoulders 10 below which the slots overlap one another. Lateral re- 110

- cesses 11 are provided in the outermost side walls 12 of the slots, the inner walls 13 of said lateral recesses being curved at their lower edges as indicated at 14.
- 5 At points in the body and eccentric to the longitudinal axis of the body sufficiently above the top of the sockets 7 to leave the spring seats 15, there are provided spring chambers 16, and the top of said chambers 10 communicate with and are accessible through recesses 17 in and located on opposite sides of said body so that through said recesses springs 18 may be inserted to rest on said spring seats.
- 15 Flat-faced overlapping cutting blades 19, which may together form a laterally expanding fan-like cutter of fish-tail shape at the lower end, are fitted and reciprocably mounted in the slots 6, respectively; and are 20 provided with shanks 20 to substantially fit the slots 6 throughout a considerable extent thereof, said shanks terminating in tongues 21, perforated to form bearings 22 through which pins 23 are inserted to pivotally connect to the tongues of said blades the forked rods 24 that are screw-threaded at their upper ends and extend through the springs 18 and through washers 25 thereon to receive nuts 26 by which the springs can be 25 put under any desired tension to yieldingly hold the cutting blades up in the slots and sockets as in Figs. 1 and 6 and to allow said blades to be drawn down to slide and fold along-side of one another as in Fig. 5.
- 30 The cutting blades 19 are provided on their outer edges with ease engaging shoulders 27 which contact with the edges of the walls 8 and from said shoulders downward said blades are provided externally with 35 runner faces or shoulders 28 that diverge downwardly from the longitudinal axes of the blades to approximately a transverse line indicated at *b*—*b* Fig. 1 opposite to laterally offset shoulders 29, 30 which are 40 formed on the inner edges of the blades to fit and alternately engage the guiding and stopping shoulders 10 and between which inter-shoulder seats 30' extend to fit the inner edge walls 9 of the slots into which the 45 blades may be inserted. Said guiding and stopping shoulders 10 come into opposition with the corresponding shoulders 29 and the edges of the walls 8 come into opposition with the corresponding shoulders 27 and the 50 inter-shoulder seats 30' come into opposition with the corresponding inner edge walls 9 so as to simultaneously fit together when the shanks 20 of the blades are fully drawn up into the slots 6 as in Fig. 1; and each 55 blade is provided at its shank with a lateral stud 31 to enter the lateral recess 11 when the shank is thus fully seated in the slot and said stud fits the recess so as to prevent looseness and displacement of the blade 60 when thus drawn up. The curved recess

edges 14 aid in quickly swinging the blades into operating position; and the studs in the recesses serve as means to prevent the blades from spreading too far outward.

The blades 19 are provided at their lower ends with curved and laterally extending cutting edges 32, the tips 33 of which project outwardly in a well-known manner common to fish-tail bits, but which terminate mid-way of the produced planes of the runner faces 28; and the outer edges 34 of said cutter blades between the runner faces 28 and the flare of the cutting edges at the tips 33 are practically parallel with the inner vertical edges 35 which extend from the shoulders 29 to the inner tips of the cutting edges, so that when said cutter blades are held fully seated in their slots 6 by the tension of the springs 18 the axes of the blades and the inner edges 35 will be in parallelism 85 with the produced axis of the tool body and the inner edges will overlap one another and the cutting edges 32 will practically meet, as indicated in Figs. 1 and 6.

The cutting edges 32 of the blades are of 90 substantially the same length as the diameter of the body 1 so as to maximize the width or diameter of the cutting edges when the blades are in the operating position Fig. 6 with their cutting edges projecting beyond 95 the produced circumferential plane of the body; and so as to fold along-side of one another within said produced circumferential plane when the blades are in retracted position Fig. 5.

From the foregoing it is clear that by pivotally mounting the cutter blades 19 eccentric to the longitudinal axis of the body 1 and substantially at the periphery of the body and by overlapping the blades, the 105 total length or working diameter of the combined cutting edges 32 is but a trifle less than twice the diameter of the cutter body 1; and that a produced axial plane of the body intersects the cutting edges of the 110 blades when the blades are in said operating position and also when the blades are in said retracted position. Each blade is further provided at the inner edge of its shank 20 with an offset 36 extending up from the 115 shoulder 30 at the termination of the shank, the purpose of said offset being to allow the cutter blade to be swung inwardly when the cutter blade is pulled down relative to the tool body for that purpose, thus to retract the tips 33 of the cutting edges from the produced vertical planes in which the runner faces 28 are brought when the blades are drawn downward; the result being that when the blades are in the positions shown 120 in Fig. 5 the runner faces will run on the inside of the casing 37 and will hold the cutter tips from engagement with the casing as the tool descends through the casing, it being evident that after the runner faces have 125 130

escaped from the lower end of the casing the springs 18 acting upon the blades will expand the blades to their original cutting width as shown in Figs. 1 and 6; and will also bring the downwardly slanting shoulders 28 underneath the casing to engage the same and slide therepast, thus retracting the blades into the running position shown in Fig. 5, when it is desired to withdraw the tool from below the casing. As the springs 18 thus draw the blades 19 upward the studs 31 riding on the curved edges 14 of the lateral recesses 11 assist in expanding the blades to cutting position. The upper ends 15 of the spring chambers 16 are provided with removable closures as plugs 38 which may be screw-threaded into said ends.

When the cutting edges become worn the blades may be withdrawn from the tool by 20 simply removing the washers, nuts and plugs 25, 26 and 38 and pulling the blades 19, with their forked rods 24, out of the tool body 1 whereupon said rods may be detached from the blades if desired and the blades 25 sharpened or discarded, depending upon the amount of wear that has occurred, it being understood that each blade may be repeatedly sharpened until the blade is practically worn out whereupon it is discarded.

It is obvious that as soon as the blades 30 have been removed new blades may be installed and the tool be put to work without waiting for re-sharpening.

I claim:

1. A rotary boring tool comprising a body 35 having two substantially separate longitudinal slots, overlapping cutter blades reciprocably mounted in and projecting from said slots, and means to hold the cutter blades outward when the blades are moved in one direction, said blades being provided with runner faces extending substantially parallel to the axis of the body when the blades are folded.

2. A rotary boring tool comprising a body 45 having two substantially separate longitudinal slots with adjacent sides formed substantially in a single plane, and cutter blades projecting from said slots, each blade having a shoulder to engage the body and provided 50 downwardly from said shoulder with a runner face diverging downwardly from the longitudinal axis of the blade.

3. A rotary boring tool comprising a body 55 having two substantially separate longitudinal slots with adjacent sides formed substantially in the mid-plane of said body, and overlapping cutter blades projecting from said slots to form runner faces along their outer edges adapted to project beyond the 60 periphery of the body when the blades are out of commission.

4. A rotary boring tool comprising a body 65 having longitudinal slots one on each side of the axis of the body with adjacent sides formed substantially in the mid-plane of

said body, and cutter blades projecting from said slots and overlapping one another, each of said blades having a shoulder on each edge thereof to seat against said body.

5. A rotary boring tool comprising a body 70 having two longitudinal slots, a shoulder in the lower end of each slot, and a cutter blade reciprocably mounted in each slot and provided with a shoulder to engage said slot shoulder when the cutter blade is moved in 75 the slot.

6. A rotary boring tool comprising a body having two longitudinal slots, a shoulder in the lower end of each slot, and a cutter blade reciprocably mounted in each slot and provided with shoulders, one of said blade 80 shoulders being brought into opposition to said slot shoulder when the blade is moved in one direction and the other blade shoulder being brought into opposition to said slot shoulder when the blade is moved in the opposite direction.

7. A rotary boring tool comprising a body having two longitudinal slots, a shoulder in the lower end of each slot, a cutter blade 90 reciprocably mounted in each of said slots, means to move the cutter blades, and laterally offset shoulders on each blade adapted to alternately engage said slot shoulder.

8. A rotary boring tool comprising a body 95 having two longitudinal slots, shoulders in opposite edges of each slot, a cutter blade reciprocably mounted in each slot, and shoulders on opposite edges of each blade to simultaneously engage said slot shoulders. 100

9. A rotary boring tool comprising a body having two longitudinal slots, shoulders in opposite edges of each slot, a cutter blade reciprocably mounted in each slot, and shoulders on opposite edges and a seat on 105 one edge of each of said blades to simultaneously engage the slot shoulders and slot edge respectively.

10. A rotary boring tool comprising a body having two longitudinal slots, the wall 110 of each slot being provided with a lateral recess, a cutter blade reciprocably mounted in the slot and adapted to swing outward, and lateral studs projecting from the blades to seat in the upper ends of the lateral recesses when the blades are swung outward. 115

11. A rotary boring tool comprising a body having two longitudinal slots, the wall of each slot being provided with a lateral recess, a cutter blade reciprocably mounted 120 in each slot and adapted to swing outward, and lateral studs projecting from the blades to seat in the upper ends of the lateral recesses when the blades are swung outward, one of the walls of each of said recesses being 125 curved at its lower edge.

12. A rotary boring tool comprising a body having a central bore, cutter blades attached along the mid-plane of the body, said bore branching to the bottom end of said 130

body to opposite sides of said mid-plane close to the blades.

13. A rotary boring tool comprising a body having a central bore, cutter blades mounted along the mid-plane of said body, and outwardly directed nozzles at the lower end of said bore and terminating in the lower end face of said body to direct streams of water along-side the cutter blades.

14. A rotary boring tool comprising a body, and two cutter blades independently pivoted at different sides of said body in a plane substantially midway between the inner and outer edges of the blades and adapted to fold along-side of one another.

15. A rotary boring tool comprising a body, cutter blades adapted to overlap one another, and pivots connecting the cutter blades to the body, said pivots being eccentric to one another in respect to the vertical axial planes of the pivots.

16. A rotary boring tool comprising a body, cutter blades adapted to overlap one another, and pivots connecting the cutter blades to the body at substantially the periphery thereof.

17. A rotary boring tool comprising a

body, cutter blades in pivotal relation to said body, and means to hold the cutter blades outward, each of said blades having a shoulder on its outer edge to seat against the body and having a runner face extending downward from said shoulder and diverging downward from the longitudinal axis of the blade, and said blades being provided at their lower ends with curved and laterally extending cutting edges having their tips projecting outwardly and terminating between the produced planes of the runner faces, and each of said blades having its outer edge between the runner face and the flare of the cutting edge parallel with the inner edge of the blade so that when the blades are in their outer position the inner edges will overlap one another and the cutting edges will practically meet.

In testimony whereof, I have hereunto set my hand at Los Angeles, California, this 12th day of March, 1913.

WILLIAM LINCOLN DUNN.

In presence of—

JAMES R. TOWNSEND,
GEORGE H. HILES.
